The ornamental design for a wearable display device, as shown and described.

DESCRIPTION

Related U.S. Application Data

(62) Division of application No. 29/433,051, filed on Sep. 25, 2012, now Pat. No. Des. 710,928.

FIG. 1 is a front perspective view of a wearable display device according to our design;

(51) **LOC (10) Cl.** **14-02**

FIG. 2 is a front elevation view of the wearable display device;

(52) **U.S. Cl.**

FIG. 3 is a back elevation view of the wearable display device;

USPC **D14/372**; D16/300

FIG. 4 is a right elevation view of the wearable display device;

(58) **Field of Classification Search**

FIG. 5 is a left elevation view of the wearable display device;

CPC G02B 27/017; G02B 27/0158; G02B

FIG. 6 is a top elevation view of the wearable display device; and,

27/0161; G02B 27/0181; G02B 27/0185;

FIG. 7 is a bottom elevation view of the wearable display device.

G02B 27/0189; G02B 2027/0178; G02C 11/10

Broken lines are environmental only and form no part of the claimed design.

USPC D14/356-358, 361, 370, 372, 385, 388,

Dash-dot lines adjacent un-shaded areas represent bounds of the claimed design and form no part of the claimed design themselves.

D14/432-439, 447, 458, 474, 480.1, 483,

The pairs of closely adjacent, spaced jagged broken lines in the drawings form no part of the claimed design and the portions between such pairs of jagged broken lines are broken away to disclose indeterminate length. Portions of the design that may be visible between the jagged lines have been

D14/484.1, 217, 239, 299; D8/349, 354,

removed for clarity.

D8/395; D16/100, 330, 300, 309; 345/7-9;

351/158; 359/633, 630
